MATCH DISPLAY AND HOLDER

Morris A. Bell, Oshkosh, Wis., assignor to The
Bell Machine Company, Oshkosh, Wis.

Application June 27, 1935, Serial No. 28,754

1 Claim. (Cl. 206—29)

This invention relates to match displays and holders in which the match combs are so arranged that the match heads take a convex arcuate formation, and in some cases the match combs 5 may be replaced in the holders as a unit as the supply is exhausted and likewise the scratching surface replaced as required.

Heretofore in my copending application Serial No. 706,895, filed January 16, 1934, Patent No. 10 2,067,820, granted Jan. 12, 1937 match combs have been rolled so as to provide a convex match head surface, but as soon as the matches are exhausted, the holder has no further utility since the base portion of the match comb is glued into 15 the holder and it is difficult to remove it from the holder for replacement purposes. Further I have heretofore confined this use to a rolled match comb, whereas my present invention contemplates the use of the match combs in parallel 20 relation to each other in a substantially rectangular holder.

One of the objects of the invention is to provide a rectangular holder into which is placed a plurality of parallel match combs, the base of the 25 match combs arcuately arranged so as to provide a convex surface of match heads.

Another object is to secure the base portion of the match combs together in parallel relation to each other by adhesive or other securing means, 30 the base portion of the match combs arranged in arcuate relation in each other, the whole to comprise a unit for replacement purposes or initial installation in the holder, and the scratching surface for igniting the matches is secured to a plug 35 which likewise forms the bottom of the holder and may be replaced as the scratching material is exhausted.

Still another object is to utilize a match comb having a tapering base, which, when rolled with 40 the wide portion of the comb innermost, will result in a flat bottom surface and a concave match head surface. The match comb can be removed as a unit, as well as the plug carrying the igniting material, for replacement purposes.

45 Other objects will be disclosed in the specification and claim forming a part of this application.

In the drawing:

Figure 1 is a vertical section of the preferred 50 form illustrating a plurality of match combs in parallel relation to each other in a rectangular holder in which is formed a socket having a dome-shaped bottom;

Figure 2 is a vertical section taken on line 55 2—2 of Figure 1;

Figure 3 is a vertical section of a modified form in which the parallel match combs are formed as a unit before being placed in the holder and provides for a removable plug at the bottom;

Figure 4 is a vertical section taken on line 4—4 of Figure 3;

Figure 5 is a vertical section of a further modified form in which the match comb tapers and is rolled to fit into a circular socket;

Figure 6 is a side elevation of the match comb shown in Figure 5 removed from the socket; and

Figure 7 is a bottom plan of the holder shown in Figure 5.

Referring to the drawing, in which similar parts are designated by like numerals:

Numerals 8 designate a holder of substantially rectangular form having inwardly sloping sides 9 and a socket 10 having a dome-shaped bottom 11 and a removable bottom portion 20, with igniting material 12 on the bottom of said holder 15. Arranged within the holder 8 are a plurality of parallel match combs 13, each match comb consisting of paper or fiber board having a solid base 14, that portion above the base slit to form 20 parallel match shanks 15, having match heads 16.

The match combs 13 are arranged on the dome-shaped bottom 11 of the socket 10 in snug relation to each other, completely filling the socket so that the match heads 16 assume a concave semi-elliptical appearance. The maximum depth of the socket 10 corresponds to the unslotted portion of the match combs, so that the outermost combs 17 and 18 will have the inner edge 19 of the socket 10 as a binding or tearing fulcrum. As 35 the matches are detached from the outside toward the middle, the base portions of the match combs within the socket serve to perpetuate the fulcrum or tearing points. The match combs may be secured together at their bases by adhesive or metallic means and in turn secured to the socket, or close frictional contact between the match combs and the walls of the socket may be the sole confining means. Due to the tapering walls of the socket 10 and the greater diameter of the match 40 heads 16, the matches will assume a flaring position which permits very attractive designs to be formulated on the exposed undersurface of the match heads through the use of varied colored match heads.

The form of holder shown in Figures 1 and 2 may be molded as an integral member.

In the modified form of the invention as illustrated in Figures 3 and 4, the same parallel match combs are used, but before being placed in the 55

holder 8, the match combs 13 are assembled on an oval or concave former, formed into a unit by adhesive or other means, and inserted in the socket 10. In this modification, however, no dome-shaped bottom is utilized, the bottom portion 20 taking the form of a removable plug having igniting material 12 on its outer face, and upon removal giving access to the socket 10 so that the base portion 14 of the combs 13, after the match heads have been detached, can be readily removed for refill purposes. Likewise, a new plug 20 carrying fresh igniting material 12 may be utilized upon the igniting material becoming exhausted.

15 In the modified form of invention shown in Figures 5, 6, and 7, I contemplate the use of a single match comb 21 having a tapered base 22, which may be rolled so that the wide portion of the base will be innermost and inserted in a circular socket 23. Under this arrangement, the flaring concave surface of match heads will be presented with the bottom edge of the match comb 21 on the same horizontal plane and resting on the removable plug 20, thus enabling the core or base 22, after 25 the matches have been exhausted, to be removed and a new match unit inserted.

Obviously, I do not confine myself to the use of a tapered match comb as the flaring concave bed of match heads may be formed in other ways, 30 such as by the use of a former as was suggested in connection with Figure 3. Additional rolled match combs may be supplied for replacement purposes.

As actually used in the modified form of the invention, the matches will be used from the outside in, and upon being exhausted, the plug or bottom 20 is removed, the remaining core or base 14 forced out, and a new match unit inserted; 5 and, if the igniting material 12 on the plug 20 is exhausted, a new plug may be inserted having igniting material on its bottom surface.

Numerous variations may doubtless be devised by persons skilled in the art without departing 10 from the principles of my invention. I, therefore, desire no limitations to be imposed on my invention, except such as are indicated in the appended claim.

What I claim is:

15 A match package comprising a holder having a substantially rectangular slot formed therethrough from top to bottom, opposite side walls of which converge in a downward direction, a match brush comprising a plurality of match 20 combs having unslotted portions arranged in parallel contiguity forming a solid base adapted to be inserted into the upper end of said slot and to seat frictionally against the convergent sides thereof, and a removable bottom closing the lower 25 end of said slot, giving access to the base of said match brush when removed permitting the latter to be unseated, for purpose of replenishment of said match brush.
